UNITED STATES PATENT OFFICE.

AVILA O. THOMAS, OF DETROIT, MICHIGAN.

BUILDING TILE.

1,413,241.

Specification of Letters Patent. Patented Apr. 18, 1922.

Application filed January 20, 1921. Serial No. 438,570.

To all whom it may concern:

Be it known that I, AVILA O. THOMAS, a citizen of the United States, residing at Detroit, in the county of Wayne and State of Michigan, have invented a new and useful Building Tile, of which the following is a specification.

This invention relates to building tiles and has particular reference to a building tile adapted for wall construction employing the tie member disclosed in applicant's copending application, Serial Number 438,569, filed January 20, 1921.

It is the object of the invention primarily to provide a building tile adapted for use in complementary pairs to form hollow blocks, and which are provided with apertures formed with exterior pockets to receive the heads and tensioning elements of transverse tie members whereby the tiles are maintained in their paired block-forming position, and the ends of the tiles are firmly held in proper abutting relation.

In attaining this object the invention contemplates forming apertured V-shaped pockets in the exterior face of the tiles adjacent their extremities so that one wall of each pocket may form a right-angled abutment for a tie member diagonally connecting tiles of abutting blocks, and in which the extremities of the tie members will be embedded flush with the exterior of said blocks, and said pockets will also serve as anchorage receptacles to afford a maximum retention of the plastic finishing coat usually applied to the wall.

A preferred embodiment of the invention is hereinafter described and is illustrated in the accompanying drawing, wherein,

Fig. 1 is a view in exterior elevation of a portion of a wall formed of the herein-described tiles.

Fig. 2 is a horizontal sectional view showing several abutting walls formed in accordance with the invention.

Fig. 3 is a perspective view of one of the tile elements.

Fig. 4 is a perspective view of a wedge employed to tension the tie members which join the tiles shown in Fig. 2.

In these views the reference character 1 designates a tile, either baked or air-dried, which comprises a flat rectangular plate having ribs 2 and 3 projecting from one of its faces, the ribs 2 being set back from the respective ends of the tile, and the ribs 3

extended between the ribs 2, respectively along the top and bottom edges of the tiles. Said tiles are arranged in complementary pairs to form hollow building blocks, the 60 plates 1 of each pair being parallel and the ribs 2 and 3 abutting. When a wall is formed of tiers of said blocks, with the end joints of said blocks vertically registering, 65 columnar openings 4 are formed at said joints, between the ribs of adjacent blocks and the end portions of the plate 1. Four tie members 5 are diagonally arranged across the opening 4 to connect each two abutting blocks and arranged to form transverse pairs. Said ties, which form the subject of a copending application, are formed of sheet metal, each having one end bent to form a T-shaped head 6 and being return-bent at their other ends 7 to be engaged by 70 tensioning wedges 8. Said ties function both to establish a bond to maintain the end-abutting relation of adjacent blocks, and to maintain the proper complementary relation of the tiles forming each block. Pairs of 80 V-shaped pockets 9 are formed in the exterior faces of the tiles, respectively adjacent the ends thereof, the pockets of each pair being extended toward each other from the upper and lower marginal edges of the 85 block so that the vertically aligned pockets 9 at adjoining edges of the blocks are in communication, as is best seen in Fig. 1. The heads 6 and tensioning means 7 of each tie member are disposed within the respective 90 pockets 9, one wall of each pocket being transverse to the corresponding tie member 3 to form a right-angle abutment for the head 6 or wedge 8 of said tie, and said wall being apertured as indicated at 10 to give 95 passage to said tie member therethrough.

At the intersection of two exterior walls of a building employing the improved tile construction, special corner tiles 11 are employed (see Fig. 2), each abutting against 100 the outer tile members of the abutting end blocks of the two walls, said blocks and special tiles forming a columnar opening 12 of substantially twice the size of the openings 4. The large opening 12 is traversed in the 105 direction of its major axis by an especially long tie member 5 connecting the exterior tiles of the abutting blocks of the two transverse walls, and transverse tie members extend across said opening connecting the tiles 110 11 to each of the inner tiles 1 of the end blocks of said transverse walls.

It is to be noted that the pockets 9, in addition to receiving the heads and tensioning means of the tie members 5, further offer a retention to the usual finishing coating of the wall, both interiorly and exteriorly thereof. Also it is an advantageous feature of the invention that the V-pockets 9 are formed in opposed relation to the ribs 2 into which the depressions forming said pockets 10 extend, so that the walls of the tiles resulting from the presence of said pockets are not materially weakened and are maintained substantially uniform in thickness.

What I claim is:

- 15 1. In a wall construction, a row of blocks and tie members diagonally connecting said blocks at their joints, said tie members having heads and tensioning means, and said blocks having V-shaped pockets in their exterior faces to receive the heads and tensioning means of said tie members, one wall of each pocket being substantially transverse to the associated tie member to form a suitable abutment for the head or tensioning means 25 of said member.
2. In a wall construction, superposed rows of blocks and tie members diagonally connecting the blocks of each row, said tie members having heads and tensioning means, and said blocks having pockets respectively adjacent their upper and lower edges to receive the heads and tensioning means of said tie members, the pockets adjacent adjoining

edges of superposed blocks being in communication.

35

3. In a wall construction, a row of blocks each comprising two tiles having abutting ribs set back from their vertical edges and having in their exterior faces V-shaped pockets opposite said ribs, the abutting end portions of the tiles and said ribs co-acting to form an opening, tie members extending diagonally of said opening between the opposite tiles of adjacent blocks, and tensioning means for said ties engaged in certain 40 of said pockets.

40

4. A building tile having ribs upon its interior face set back from its ends, and having pockets in its exterior face opposite said ribs for receiving the tensioning elements of 45 tie members.

45

5. In a wall construction, a row of blocks each comprising two tiles having abutting ribs set back from their vertical edges and having in their exterior faces V-shaped 50 pockets opposite said ribs, the abutting end portions of the tiles and said ribs co-acting to form an opening, tie members extending diagonally of said opening between the opposite tiles of adjacent blocks, tensioning 55 means for said ties engaged in certain of said pockets, and a cementitious filling in said opening embedding said tie members.

55

In testimony whereof I sign this specification.

AVILA O. THOMAS.
